(57) **CLAIM**

The ornamental design for a hanging decoration, as shown and described.

DESCRIPTION

FIG. 1 is a perspective view of a hanging decoration showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of a hanging decoration shown with a curved tip pine cone in broken lines in a used condition;

FIG. 9 is a perspective view of a hanging decoration shown with a triangular tip pine cone in broken lines in a used condition; and,

FIG. 10 is a perspective view of a hanging decoration shown with a flat, rectangular tip pine cone in broken lines in use condition.

The bell hanging decoration claimed is for hanging on a Christmas tree or hanging indoors or outdoors as a decoration article. The bell hanging decoration according to my design is a housing with a surface designed as a pine cone and the bottom of the housing is a bottom chassis with a bead to form a bell.

The broken line showing of a pine cone is included for the purpose of illustrating only and forms no part of the claimed design.
